Patented June 6, 1972

223,754

TONNEAU COVER FOR DUNE BUGGIES

Henry C. Arnoldy, 30417 J. Carls, and William C. Stanko,
30233 J. Carls, both of Roseville, Mich. 48066

Original design application Dec. 3, 1968, Ser. No. 14,760,
now Patent No. 216,783, dated Mar. 10, 1970. Divided
and this application Jan. 7, 1970, Ser. No. 20,789

Term of patent 14 years

Int. Cl. D12—16
U.S. Cl. D14—27

FIG. 3

FIG. 4

FIG. 5

FIG. 6

FIG. 7

FIG. 8

FIG. 1 is a perspective view of a tonneau cover for dune buggies showing our new design;

FIG. 2 is a perspective view of a modified form thereof;

FIG. 3 is a side view of the form shown in FIG. 1;

FIG. 4 is a top plan view thereof;

FIG. 5 is a perspective view of another modified form thereof;

FIG. 6 is a perspective view of still another modified form thereof;

FIG. 7 is a side view of the form shown in FIG. 5; and,

FIG. 8 is a top plan view thereof.

This a divisional application of application, Ser. No. D. 14,760, filed Dec. 3, 1968, now Pat. No. D. 216,783.

We claim:

The ornamental design for a tonneau cover for dune buggies, substantially as shown and described.
